UNITED STATES PATENT OFFICE

CHRISTIAN C. MILLHEAM, OF BELOIT, WISCONSIN

WIRE PLIERS

Application filed July 18, 1929. Serial No. 379,255.

The invention relates to pliers for twisting wires together or for holding them while the twisting is being done by some other means, some of the principal uses of the tool being in the field of line erection and maintenance and in the construction of forms for cement work.

It is the principal object of the invention to provide a simple and inexpensive, yet an efficient and desirable tool in which the wires have no tendency to open the jaws by which they are held.

A further object is to provide a unique construction in which the two jaws are effectively held against any relative movement whatever except about the pivot by which they are connected.

With the foregoing in view, the invention resides in the novel subject matter hereinabove described and claimed, description being accomplished by reference to the accompanying drawing.

Fig. 1 is a side elevation showing the pliers open and engaged with two pieces of wire.

Fig. 2 is an edge view showing the pliers closed.

Fig. 3 is a vertical sectional view partly in elevation as indicated by line 3—3 of Fig. 2.

Fig. 4 is a sectional view on line 4—4 of Fig. 3.

Figs. 5 and 6 are perspective views of the front portions of the two crossed levers, said portions constituting the jaws of the pliers.

Fig. 7 is a perspective view of a plate which forms part of the front portion of one of the levers.

In the drawing above briefly described, the numerals 8 and 9 denote two crossed levers pivoted together at their crossing point as denoted at 10, the rear ends of said levers constituting handles. The front end 11 of the lever 8 is shorter than the front end 12 of the lever 9, and the front edge of said short lever end 11 is formed with a notch 13 having a straight rear wall 14 and opposed side walls 15, the rear wall 14 being preferably at about right angles to the length of the tool while at least one of the side walls 15 is preferably at a slightly acute angle to

said rear wall 14. This rear wall is preferably of such shape transversely as to provide it with the convex form seen more particularly in Fig. 4.

The relatively long front end 12 of the lever 9 is provided with an integral lug 16 which projects beyond its inner edge 17, in front of the lever end 11, said lug 16 being provided with a straight rear edge 18 extending across the notch 13 and cooperating with the latter in forming an elongated slot (Fig. 3) to receive wires W while twisting them together with the pliers or while holding them with the pliers incident to twisting with some other means. The edge 18 of the lug 16 is opposed to the rear wall 14 of the notch 13 and both of these formations are transverse to the length of the tool. Thus, when they receive pressure from the wires W, such pressure is exerted forwardly on one jaw of the pliers and rearwardly on the other jaw and has no tendency whatever to separate said jaws, so that the operator need not continually force the handles together with great force, as in the ordinary pliers.

The front edge portion 19 and the inner edge portion 20 of the lever end 11, are preferably thinned to a thickness less than that of the lever end 12 and its lug 16, and the inner edge 17 of said lever end 12 and the rear edge 18 of said lug 16, are grooved at 21 and 22 respectively, to receive said thinned lever portions 19—20. This construction effectively locks the two jaws of the pliers against any relative movement other than that which may take place about the pivot 10. Moreover, the transversely convex form of the notch wall 14, tends to distort the wires W somewhat into the groove 22, thereby effectively holding said wires against relative longitudinal sliding while they are being twisted together.

In the preferred form of construction, the thinned portions 19—20 are formed by the front and inner edges of a hard metal plate 23, in which plate the notch 13 is formed. This plate forms the front extremity of the lever 8 and is secured in a recess 24 of the major portion of said lever, by rivets or the like 25. When one plate becomes worn, it

may be removed and another substituted. However, the construction under consideration is intended primarily to permit the installation of plates having notches 13 of any desired sizes, according to the size of wire 5 to be held or manipulated with the pliers.

Excellent results have been obtained from the details disclosed and they are therefore 10 preferably followed. Within the scope of the invention as claimed however, variations 15 may be made. Particular attention is invited to the fact that the pressure of the wires against the tool jaws, has no tendency to open the latter, this being due to the relation of jaws herein described, which relation I term 20 "off-center jaws".

I claim:—

1. Wire pliers comprising two crossed levers pivoted together at their crossing 25 point, the front end of one of said levers being shorter than the front end of the other lever and being provided in its front edge with a wire-receiving notch, said notch having a rear wall and opposed side walls, said 30 rear wall being transverse to the length of the pliers while said side walls extend in planes longitudinally of said length, said other lever end being provided with a lug projecting from its inner edge in front of 35 said short lever end and extending across said notch, said lug having a rear edge opposed to and spaced forwardly from said rear wall of said notch, said rear and side walls of said notch and said rear edge of said lug 40 co-operating in forming a wire-receiving and holding slot when the levers are in closed 45 position.

2. A structure as specified in claim 1; said short end of said one lever being thinned at 50 its front and inner edges to a thickness less than that of said front end and lug of the other lever, said front end and lug of said other lever being grooved to snugly receive 55 said thinned edges of said one lever end.

46 3. A structure as specified in claim 1; said short end of said one lever being thinned at 60 its front and inner edges to a thickness less than that of said front end and lug of the other lever, said front end and lug of said other lever being grooved to snugly receive 65 said thinned edges of said one lever end, said rear wall of said notch being transversely convex to slightly distort the wires into the groove of said lug.

47 4. Wire pliers comprising two crossed levers pivoted together at their crossing point, the front end of one of said levers being shorter than the front end of the other lever, the front extremity of said short lever 70 end being formed by a relatively thin plate secured to the major portion of this lever, the front edge of said plate being formed with a notch having a rear wall and two opposed side walls, said rear wall being transverse to the 75 length of the pliers while said side walls ex-

tend in planes longitudinally of said length, the relatively long front end of said other lever being provided at its inner edge with a lug which projects in front of said short lever end and is provided with a rear edge 80 extending across the aforesaid notch, said rear lug edge being grooved to receive the front edge of the aforesaid plate, said inner edge of said relatively long lever end being grooved to receive the inner edge of said 85 plate.

In testimony whereof I have hereunto affixed my signature.

CHRISTIAN C. MILLHEAM.
